UNITED STATES PATENT OFFICE.

STEPHEN AUGUSTUS HASBROUCK, OF NEW YORK, N. Y.

REGULATOR FOR GASOLENE OR OTHER LIKE ENGINES.

SPECIFICATION forming part of Letters Patent No. 654,894, dated July 31, 1900.

Application filed August 5, 1899. Serial No. 726,245. (No model.)

To all whom it may concern:

Be it known that I, STEPHEN AUGUSTUS HASBROUCK, a citizen of the United States, residing in the borough of Manhattan, in the city, county, and State of New York, have invented certain new and useful Improvements in Regulators for Gasolene or other Like Engines, of which the following is a specification.

My invention consists of an improved mechanism for regulating the fuel-supply in gasolene and other like engines by increasing or diminishing the quantity of explosive mixture supplied to the engine and at the same time preserving the proper proportions of atmospheric air and hydrocarbon vapor. In such engines the fuel supplied to the cylinder in which the explosion takes place consists of a mixture of atmospheric air and gas or vaporized oil combined in proper proportions, and the power of the engine may be regulated by changing the quantity of the supply.

The object of my invention is to provide a simple and efficient mechanism for regulating the quantity of fuel supplied and at the same time preserving the proper proportion of the ingredients.

My invention is illustrated in the accompanying drawings, showing so much of the mechanism as is necessary to an understanding thereof.

Figure 1 is a front elevation of the mechanism. Fig. 2 is a cross-section thereof through the plane X Y of Fig. 1. Fig. 3 is a detailed view of part of the regulating mechanism. Fig. 4 is a perspective view of the air-valve. Fig. 5 is a view in cross-section of a simplified modification of the mechanism shown in Fig. 2. Figs. 6 and 7 show modified forms of the lever 9 and its connections.

Similar letters and numbers refer to similar parts in the several views.

A is a chamber containing the gasolene or other liquid hydrocarbon, which is admitted by the pipe B and kept at a constant level by the overflow-pipe C or other suitable means. The pipe B is connected with the main source of fuel-supply by a feed-pump or other suitable means. The liquid fuel passes from the chamber A through the aperture D to the needle-valve 1. This needle-valve is free to move longitudinally through the sleeve or regulating-screw 2 and is provided with a

shoulder 23, which engages with the lower extremity of such regulating-screw. The screw 2 is in screw-threaded engagement with the casing of the chamber, as indicated in the drawings, and when adjusted to the desired position may be locked in place by the setscrew 3. An expansion-spring 4, between the upper end of the screw 2 and the head 24 of the needle-valve 1, tends to raise the valve and holds the shoulder 23 in engagement with the lower end of screw 2.

5 is a rotary air-valve provided with a plurality of suitable apertures set upon a stationary seat 7 of similar construction and provided with corresponding apertures and operated by a shaft 6, which is in turn actuated by a crank 8, provided with a link 13, attached thereto by a pin 14. This crank may be connected with the governor of the engine or simply turned when desired by the operator of the mechanism. In the latter case the link 13 may be provided with a suitable handle. A connecting-rod 10 connects the crank 8 with one extremity of the lever 9, which is hinged at its other extremity 21 upon a support 22. Through a screw-threaded aperture in the lever, directly over the head of the needle-valve, passes a screw 15, which may be locked in any desired position by a lock-nut 16, and the lower extremity of which is in contact with or close juxtaposition to the head 24 of the needle-valve when the lever is in its normal position.

20 is a vaporizing-chamber connected by the pipe 12 with the admission-valve of the cylinder and divided by a screen or partition 11, of wire-gauze or other suitable material, placed directly under the aperture 25, leading downward from the needle-valve 1. The air, entering by the air-valve 5 7, passes through the screen 11, over which the gasolene or other liquid fuel flows after leaving the needle-valve 1, and takes up the liquid fuel in the form of vapor, thus producing the explosive mixture, which is transmitted to the admission-valve of the cylinder by the pipe 12. There are, however, other forms of vaporizer which may be used in conjunction with my invention, and I do not limit myself to the particular form of vaporizer herein shown and described.

In the simplified modification of my inven-

tion shown in Fig. 5 the regulating-screw 2 and the adjusting device 15 16 are dispensed with and the lever 9 impinges directly upon the head 24 of the needle-valve 1. The adjustment is supplied by the turnbuckle 26 and lock-nuts 27 27, with which the connecting-rod 10 is provided, whereby such connecting-rod may be made longer or shorter as required, or any other convenient means of regulating the length of such connecting-rod may be used. The spring 4 serves to restore the valve to its normal position; but this may be accomplished by any other suitable mechanism—as, for example, by suitably attaching the head 24 of the valve to the lever 9, so that the lever itself will raise the valve. Two convenient devices for such adjustment are illustrated by Figs. 6 and 7. In Fig. 6 the necessary play is secured by the slot 28. In Fig. 7 a toggle 29 is substituted for the support 22 for the same purpose.

The method of operation of the mechanism is as follows: When the engine is running at full speed, the air-valve is open to its farthest extent, and the needle-valve after having been adjusted in the proper position by the screw 2, which is then locked in place by the set-screw 3, is held by the spring 4, with the shoulder 23 in engagement with the lower end of the screw 2. When it is desired to decrease the power of the engine, the link 13 is drawn in the direction of the arrow, thus turning the crank 8 and revolving the air-valve 5, so that its openings no longer coincide with the openings in the seat 7 and the supply of air is correspondingly decreased. The motion may be imparted to the link 13 by the operator or by the governor of the engine or by other convenient means, as hereinbefore suggested. The same motion, acting upon the connecting-rod 10, draws down the lever 9, which by means of the screw 15 depresses the needle-valve 1 and so reduces the supply of gasoline or other fuel fed through the valve. To increase the power, the above-described operation is reversed. The link 13 is brought back to its original position, thus turning the crank 8, revolving the shaft 6, and reopening the air-valve, and at the same time raising the lever 9, and thus releasing the needle-valve, which is brought back to its original position by means of the spring 4. Any excess of gasoline falling to the bottom of the vaporizing-chamber is carried off by the overflow-pipe 17.

The screw 2 serves the purpose of fixing the normal position of the needle-valve and so regulating the amount of gasoline to be admitted when the air-valve is open to its farthest extent, and while useful to prevent waste of fuel is not essential to the operation of the engine. The screw 15 furnishes a convenient means of adjusting and regulating the action of the lever 9 upon the head of the needle-valve, but is not indispensable, and the lever may be constructed so as to impinge directly on the head of the valve, as

shown in the modification illustrated by Fig. 5, in which any necessary adjustment is effected by regulating the length of the connecting-rod 10, or the lever may be connected with the head of the valve-stem and the spring dispensed with, as shown in Figs. 6 and 7.

What I claim as new, and desire to secure by Letters Patent, is as follows:

1. The above-described mechanism for adjusting the fuel-valve in gasoline and other like engines, comprising in combination a needle-valve, a regulating-screw in engagement with a screw-threaded aperture in the casing of the fuel-chamber, and provided with an aperture through which the stem of the needle-valve passes, a set-screw adapted to hold said regulating-screw in position, a shoulder upon the valve-stem engaging with the lower end of the regulating-screw, and an expansion-spring between the upper end of the regulating-screw and the head of the valve-stem, all constructed and operating as and for the purposes specified. 90

2. An improved regulator for gasoline and other like engines, comprising in combination a rotary air-valve, a needle fuel-valve, a shaft actuating said air-valve, and provided with a crank, which is connected by means of a connecting-rod with a lever adapted to depress the fuel-valve proportionately with the closing of the air-valve, by pressure upon the head of the valve-stem, and means for automatically restoring the fuel-valve to its normal position when the air-valve is reopened. 95

3. An improved regulator for gasoline and other like engines, comprising in combination a rotary air-valve, a needle fuel-valve, a shaft actuating said air-valve, and provided with a crank, which is connected by means of a connecting-rod, adjustable as to length, with a lever adapted to depress the fuel-valve, proportionately with the closing of the air-valve, by pressure upon the head of the valve-stem, and means for automatically restoring the fuel-valve to its normal position when the air-valve is reopened. 105

4. An improved regulator for gasoline and other like engines, comprising in combination a rotary air-valve, a needle fuel-valve, a shaft actuating said air-valve, and provided with a crank, which is connected by means of a connecting-rod with a lever adapted to depress the fuel-valve, and provided with means for adjusting the pressure of the lever upon the head of the valve-stem, and means for automatically restoring the fuel-valve to its normal position. 115

5. An improved regulator for gasoline and other like engines, comprising in combination a rotary air-valve, a needle fuel-valve, a shaft actuating said air-valve, and provided with a crank which is connected by means of a connecting-rod with a lever in operative relation with the head of the valve-stem to operate the fuel-valve in proper proportion as the air-valve is operated. 120

6. An improved regulator for gasoline and

other like engines, comprising in combination a rotary air-valve, a needle fuel-valve, a shaft actuating said air-valve, and provided with a crank, which is connected by means of a connecting-rod, adjustable as to length, with a lever in operative relation with the head of the valve-stem, to operate the fuel-valve in proper proportion as the air-valve is operated.

In testimony whereof I have signed this specification in the presence of two subscribing witnesses.

STEPHEN AUGUSTUS HASBROUCK.
